FIG. 1.

FIG. 2.

FIG. 3.

FIG. 4.

FIG. 5.

The side of the combined table and chair not depicted in the drawings is identical in appearance to the side shown in FIGURE 3.

I claim:

The ornamental design for a child's combined table and chair, substantially as shown and described.
